Frederick C. Johnson, Jersey Shore, Pa.

Application June 18, 1948, Serial No. 147,055

Term of patent 3½ years

(Cl. D14—18)

To all whom it may concern:

Be it known that I, Frederick C. Johnson, a citizen of the United States, residing at Jersey Shore, in the county of Lycoming and State of Pennsylvania, have invented a new, original, and ornamental Design for an Automobile Hood Ornament, of which the following is a specification, reference being had to the accompanying drawings, forming a part thereof.

Figure 1 is a side elevational view of an automobile hood ornament, showing my new design;

Figure 2 is a top plan view of the same;
Figure 3 is a front end view of the same;
Figure 4 is a rear end view of the same.

I claim:

The ornamental design for an automobile hood ornament, as shown.

FREDERICK C. JOHNSON.
